UNITED STATES PATENT OFFICE.

WILLIAM L. DITGES, OF PITTSBURGH, PENNSYLVANIA, ASSIGNOR TO MACKINTOSH-HEMPHILL COMPANY, OF PITTSBURGH, PENNSYLVANIA, A CORPORATION OF PENNSYLVANIA.

MANIPULATOR FOR ROLLING MILLS.

Application filed January 16, 1922. Serial No. 529,518.

To all whom it may concern:

Be it known that I, WILLIAM L. DITGES, residing at Pittsburgh, in the county of Allegheny and State of Pennsylvania, a citizen of the United States, have invented or discovered certain new and useful Improvements in Manipulators for Rolling Mills, of which improvements the following is a specification.

10 The invention described herein relates to certain improvements in manipulators for rolling mills and has for its object the provision of means whereby the piece being rolled may be turned through an arc of 180 degrees, the improvements being especially adapted for turning a slab or piece having a width substantially greater than its thickness. The invention is hereinafter more fully described and claimed.

20 In the accompanying drawing forming a part of this specification, Fig. 1 is a top plan view of a portion of a feed table having the improved manipulator combined therewith, and Figs. 2, 3 and 4 are sectional elevations of the same showing respectively different positions to which the parts are moved in turning a slab; Figures 5 and 6 are views similar to Figs. 2, 3 and 4, but illustrating a modification in the manner 30 of operating the manipulator.

The improvement claimed herein can be combined with any suitable construction of feed table known in the art. In the practice of the invention the reciprocating member of the manipulator consists of a head secured to a longitudinally movable supporting and guiding member 2 mounted in bearings 3 in a frame 4 arranged at one side of the feed table. The head which is arranged at right angles to the rollers of the feed table and is supported to move in a horizontal plane above the feed rollers, is made of a length dependent on the length of the pieces to be handled thereby. To 40 the head are connected links 5 having their opposite ends connected to rocker arms 6 on a shaft 7. This shaft may be oscillated to reciprocate the head by any suitable motor mechanism. As shown in Fig. 2 the 50 head projects a substantial distance above the rollers and has its operating face formed at an angle less than 90 degrees, to the axes of the feed rollers. The head is provided with a finger extending downwardly

between the feed rollers and forwardly of 55 the head, said finger being adapted to strike against the tail 9 extending downwardly below the axis of movement of the turning head 10. This head is pivotally mounted in brackets 11 secured to one of the side frames 60 of the feed table and is normally held with its operative face at an angle less than 90 degrees to the axes of the rollers by weights 12 connected to the turning head by flexible 65 means.

During the rolling operation the shifting head 1 is at one side of the feed table and the turning head in the position shown in Fig. 2. When it is desired to turn the 70 piece lying on the rollers, the head 1 is moved to the right thereby pushing the piece along the rollers and causing the slab to move up onto the face of the turning head as shown in Fig. 3. By a further movement of the shifting head 1 the finger 8 will strike the tail 9 and rotate the turning head to the position shown in Fig. 4 so that when the head 1 is withdrawn the 75 piece will drop onto the rolls and complete its turning movement through an arc of 80 180 degrees, and permit the turning head to be returned to the position shown in Figs. 2 and 3.

In order to facilitate the lateral movement of the piece onto the turning head the latter is provided at its lower edge with a toe or projection 13 having an inclined face which will extend to and preferably be a plane tangential to the feed roller.

As shown in Figs. 5 and 6 the weight 12 90 may be omitted, in which case the normal position of the turning head will be approximately parallel with the shifting head, as shown in Fig. 5. When a piece is moved laterally by the shifting head its edge will 95 strike against the turning head above its pivotal axis and force it to the position shown in Fig. 6. As the turning head is shifted to the position shown in Fig. 6 100 the toe 13 will pass under the piece and lift it sufficiently far to facilitate the sliding of the piece along the face of the turning head. By a continued movement of the shifting head the finger 8 will strike against the tail 9 turning the head 10 to the position shown in Fig. 4. When the shifting head is withdrawn the slab will drop onto 105 the rollers completing its turning movement,

and the head 10 will be in position for the next turning movement.

I claim herein as my invention:

1. The combination of a feed table for rolling mills, a head movable transversely of the table, a pivotally mounted head extending along the table in the path of the lateral movement of a piece, said head being adapted to be turned to receptive position by the piece being rolled and to be turned in the opposite direction by the shifting head.

2. The combination of a feed table for rolling mills with a pivotally mounted turning head provided with a forwardly projecting tail, a head movable transversely of the table and having a backwardly inclined operative face and provided with a forwardly projecting finger adapted to en-

gage the tail on the turning head to shift 20 the latter, a toe or projection on the head adapted to lift the forward edge of the piece on the feed table as the piece is moved transversely of the table.

3. The combination of a feed table for 25 rolling mills with a head movable transversely of the table and provided with a forwardly projecting finger, a pivotally mounted turning head having its operative face normally at an acute angle to the axes 30 of the rolls of the feed table and provided with a tail extending into the path of movement of the finger on the shifting head whereby the article may be turned through an arc greater than 90 degrees.

In testimony whereof, I have hereunto set my hand.

WILLIAM L. DITGES.
